The ornamental design for the ground inserted support
for a downpipe, as shown.

DESCRIPTION

FIG. 1 is a front and right side perspective view of a
ground inserted support for a downpipe, showing my
new design;

FIG. 2 is a top plan view thereof;

FIG. 3 is a rear elevational view thereof; and

FIG. 4 is a left side elevational view thereof.

FIGS. 2-4 have been shown on a reduced scale with
respect to FIG. 1.
